UNITED STATES PATENT OFFICE.

JACQUES B. RICE, OF NEW YORK, N. Y.

DESIGN FOR A COFFEE, CREAM, AND SUGAR SET.

42,950.

Specification for Design.

Patented Aug. 27, 1912.

Application filed April 21, 1910. Serial No. 556,905. Term of patent 3½ years.

To all whom it may concern:

Be it known that I, JACQUES B. RICE, a citizen of the United States of America, residing in New York, in the borough of Manhattan, county and State of New York, have invented a new, original, and ornamental Design for Coffee, Cream, and Sugar Sets, of which the following is a specification, reference being had to the accompanying drawing, forming part thereof.

The figure represents a perspective view of a coffee, cream and sugar set, showing my new design.

The design comprises the coffee pot and cream pitcher of the configuration shown, superposed as illustrated.

I claim:

The ornamental design for a coffee, cream and sugar set, as shown and described.
